(57) **CLAIM**

The ornamental design for a zippered back support, as shown and described.

DESCRIPTION

FIG. 1 is a rear view of a zippered back support showing the design with a zipper in the opened position.

FIG. 2 is a front view of the zippered back support.

FIG. 3 is a left-side view of the zippered back support. The right side view is a mirror image of the left side.

FIG. 4 is a top view of the zippered back support.

FIG. 5 is a bottom view of the zippered back support.

FIG. 6 is a front view of the zippered back support without the environmental structure.

FIG. 7 is a side-front perspective view of the zippered back support without the environmental structure; and,

FIG. 8 is a rear view of the zippered back support showing the zipper in the closed position.

The partial human figure rendered with evenly dashed lines illustrates environmental subject matter of the human body and forms no part of the claim.
